CRASH MARKER

Filed May 13, 1946

Inventor

John DeRugeris,

334 Parker Cook Attorney

UNITED STATES PATENT OFFICE

2,418,549

CRASH MARKER

John De Rugeris, Atlantic City, N. J., assignor of
one-half to Jack Budnick, Pleasantville, N. J.

Application May 13, 1946, Serial No. 669,349

3 Claims. (Cl. 9—9)

1

My invention relates to new and useful improvements in "crash markers" and has for an object to provide a relatively small housing or casing, which is to be secured within the fuselage or wings of an airplane, so that should the plane crash or drop into the sea, a weather-proof cover will be released from the casing by the action of the water, after which a buoy or float will be forced from the casing and rise to the surface of the water. In turn, from a chamber in the float will be forced telescopic rods, one of which carries a small flagstaff or signal so that the signal will extend a distance above the buoy or float and be easily ascertainable at quite a distance.

Still another object of the invention is to provide a crash marker wherein a float is normally located in a normally water-tight casing, the float in turn provided with a central chamber, while located in the chamber is a spring to force telescopic rods upwardly, while to one of the telescopic rods is secured a foldable, relatively short flagstaff together with its flag.

Still another object of the invention is to provide a crash marker wherein there is located a spring for forcing a float from a container, a spring for forcing telescopic rods from a chamber, and a third spring for forcing one of the telescopic rods to its extended position, the latter rod carrying a flagstaff which is foldable, so that the flag and the flagstaff when not in use may be housed within the chamber in the float.

Still another object of the invention is to provide a crash marker that is to be used principally on airplanes, although the same may be used in boats or ships with equally as great effect.

Still another object of the invention is to provide a crash marker that is relatively small in size, so that when installing the marker in the fuselage of an airplane, for instance, only a small circular opening has to be cut in the fuselage, over which opening, of course, will be placed a water-tight cover which is held in place by means soluble in water, so that when the crash marker is submerged, the means for holding the cover in place will be released, so that the float and its associated parts may quickly rise to the surface and mark the spot where the plane or boat has sunk.

With these and other objects in view, the invention consists in certain new and novel arrangements and combination of parts as will be hereinafter more fully described and pointed out in the claims.

Referring now to the drawings showing a pre-

2

ferred embodiment and one slight modification,

Fig. 1 is a view partly in section, showing the crash marker as having been released from its container,

5 Fig. 2 is an enlarged sectional view, showing the crash marker and a fragmentary portion of the fuselage walls of an airplane,

Fig. 3 is a horizontal, sectional view taken on line 3—3 of Fig. 2, looking in the direction of the 10 arrows,

Fig. 4 is a fragmentary, sectional view, showing a slightly modified form of cover attaching means, and

Fig. 5 is a detailed front view of the throw-over 15 link for pulling the top cover tightly into position.

Referring now more particularly to the several views, and for the moment to Fig. 1, there is shown the cylindrical casing 1 with its outwardly extending flange 2 at its upper end. This flange 20 2 is to be fitted about an opening 3 cut in the fuselage of an airplane as fragmentarily shown at 4.

It will be understood that although the crash marker is especially designed for use in the wings 25 or fuselage of an airplane, it might be used beneath the deck of a boat or ship, and it will be installed in the same manner so that when the casing and its cover become submerged, as will be shortly mentioned, the buoy or float may be released from the container.

Referring to Fig. 2 for the moment, there will be seen a metal cover 5 and a gasket 6 which is interposed between the under surface of the cover 5 and the top surface of the flange 2. In Fig. 2, 30 I have also shown spaced rivets 7 which will be freely passed through the flange 2, gasket 6, and fit within openings 8 formed in the cover 5.

The openings 8 in which the rivets 7 fit are larger than the rivets 7 and partially filled with 40 a plastic or glue 7' that is soluble in water to thus hold the rivets 7 and the cover 5 tightly to the flange 2 of the container 1. Thus, any rain or water on the outside of the cover 5 will in no way affect the inner parts of the crash marker. Should the container 1 be submerged, however, water passing around the rivets 7 will cause the plastic 7', holding the rivets 7 in place, to dissolve 45 or disintegrate and allow the cover 5 to be forced from its secured position.

Referring now for the moment to the modified form for holding the cover 5 shown in Figs. 4 and 5, instead of using the rivets 7, I use the same cover 5, which has several small peripheral lugs 9 which extend through openings 10 in the flange 55 2 of the container 1, and to these lugs 9 are

bonded lugs 11 by a cement or glue 12 that is soluble in water. On each of the other aforementioned lugs 11 is a small headed pin 13 so that a throw-over link 14 may be passed over the same, the throw-over links in turn each being secured to handles 15 mounted as at 16 about the sides of the casing 1.

There is a gasket 17 between the cover plate 5 and the rim 2, and when these handles 15 are thrown over to the position as shown in Fig. 4, the cover 5 will be pulled down and held in position until the bond 12 is dissolved, or until the throw-over links 14 are thrown over by a raising of the handles 15.

I have shown one handle and throw-over link in Fig. 4, but as they are all identical, a description of one is a description of all.

Thus it will be seen that whether the cover 5 is held as shown in Fig. 2, or held as shown in Figs. 4 and 5, the action of the water will release the cover 5 with respect to the container 1.

Referring now to Fig. 2, there will be noticed a box-like inner container 18 with its demountable lid 19. This container 18 is provided with opposite bearing points 20 to support a cable drum 21 on which is secured and wound a cable 22. Bearing against the disks or wheels 23 that form the opposite ends of the cable drum 21 may be seen a spring 24 so as to retard the pay off movement of the cable drum 21 when the float is released as will be shortly mentioned.

The lid 19 of the inner container 18 has a central opening 25 which is mounted as at 26 so as to present a smooth surface to the cable 22 as it pays off.

Located on the lid 19 of the box-like inner container 18 may be seen the spring 27, which is normally under compression, and extending therethrough is the conical end 28 of the float 29. At the end of the conical portion 28 may be seen the eye 30 in which is fastened an end of the cable 22.

It will be noticed that the top surface 31 of the buoy presses against the inner surface of the cover 5, thus holding the spring 27 firmly under compression.

The buoy or float 29 is provided with a relatively long, depending central chamber 32, in which is likewise housed a spring 33 which bears against the head 34 of one telescopic rod 35, while fitted within this telescopic rod 35 is a further rod 36, which normally holds a spring 37 in the telescopic rod 35 under compression.

To the top of the telescopic rod 36 is secured a flexible spring-like coupling 38, and to the other end of this coupling 38 is secured the flagstaff 39 with its flag or signal 40. By providing this flexible coupling 38, when the two rods 35 and 36 are telescoped or collapsed, the flagstaff 39 may be folded downwardly as shown in Fig. 2 so that the flagstaff 39 and the flag 40 may also be housed in the chamber 32 alongside of the telescopic rods 35 and 36.

In Fig. 1, there may be seen a small flange 41 on the top surface 31 of the float 29, so that the telescopic rods 35 and 36 may be fitted in position within the chamber 32 and to hold them in place when in their extended position.

It will be seen that these telescopic rods 35 and 36, flagstaff 39 and flag 40 are all normally housed within the chamber 32 of the float 29 and take up but relatively little space.

However, when the crash marker comes into operation, that is, when the container is submerged, the action of the water will cause either the bond 12 or the plastic 17 to dissolve to

thereby loosen the cover 5. At the same time, the spring 27, which is under compression, will force the cover 5 from its position and also start the buoy 29 on its upward movement. In other words, the spring 27 will insure that the float or buoy 29 will clear the container 1, after which the buoy or float 29 will continue to rise to the surface.

Also, when the float 29 is released, the spring 33 will force the larger of the telescopic rods out of the chamber 32, and the inner spring 37 will force the telescopic rod 36 to its extended position, and the spring-like coupling 38 will assume a straight or vertical position to thus raise the flagstaff 39 to its vertical position.

By utilizing the telescopic rods and flagstaff, this signal may be seen for a much greater distance than if just a buoy or float were used.

From the foregoing, it will be seen that I have provided a crash marker that occupies but little space and wherein the cover 5 may be tightly held in position, but when once released by being submerged, the float together with its telescopic rods and mast will be forced from the container, and the telescopic rods and flagstaff will be made to assume their extended position.

By providing telescopic rods and a flagstaff foldably secured to the telescopic rods, all of the parts may be encased in a relatively small chamber.

Many slight changes might be made without departing from the spirit and scope of the invention.

Having thus described my invention, what I claim as new and desire to secure by Letters Patent is:

1. In a crash marker, a container, a cover, means soluble in water for normally sealing the cover to said container, a float in said container, a cable connected to said float, spring means normally held under compression bearing against said float, said float provided with a central hollow chamber, a spring in said chamber, telescopic rods in said chamber and bearing against said spring, a further spring in one of said telescopic rods, a foldable flagstaff secured to one of said telescopic rods, said telescopic rods and flagstaff normally housed in a collapsed position in the chamber in said float, whereby when the said cover is liberated by being submerged, the float will be forced from said housing, and the telescopic rods and flagstaff will be forced from said chamber and assume an extended position.

2. In a crash marker, a container, a cover, means soluble in water for normally sealing the cover to said container, a float in said container, a drum having a cable connected to said float, a brake for retarding the movement of said cable drum, spring means normally held under compression by said float, said float provided with a central hollow chamber, a spring in said chamber, telescopic rods fitted in said chamber and bearing against said last mentioned spring, a further spring in one of said telescopic rods, a foldable flagstaff secured to one of said telescopic rods, said telescopic rods and flagstaff normally held in a collapsed position in the chamber, the flagstaff bearing against the inner surface of said cover, whereby when the said cover is liberated by submersion, the float will be mechanically forced from said housing and the telescopic rods and flagstaff will be forced from the said chamber and will assume an extended position.

3. In a crash marker, a container, a cover, means including a bond soluble in water for tightly forcing the cover on the container and normally holding the same in a sealed condition, a float in said container, a drum having a cable connected to said float, a brake for retarding the movement of said cable drum, spring means normally held under compression by said float, said float provided with a central hollow chamber, a spring in said chamber, telescopic rods fitted in said chamber and bearing against said last mentioned spring, a further spring in one

of said telescopic rods, a foldable flagstaff secured to one of said telescopic rods, said telescopic rods and flagstaff normally held in a collapsed position in the chamber, the flagstaff bearing against the inner surface of said cover, whereby when the said cover is liberated by submersion, the float will be mechanically forced from said housing and the telescopic rods and flagstaff will be forced from the said chamber and will assume an extended position.

JOHN DE RUGERIS.
